Esq. is Attorney

UNITED STATES PATENT OFFICE.

HORACE B. WENTWORTH, OF PORTLAND, MAINE, ASSIGNOR TO BELGRADE SHOE MANUFACTURING COMPANY, OF PORTLAND, MAINE, A CORPORATION OF MAINE.

SANITARY SHOE.

1,183,935.

Specification of Letters Patent. Patented May 23, 1916.

Application filed May 21, 1915. Serial No. 29,478.

To all whom it may concern:

Be it known that I, HORACE B. WENTWORTH, a citizen of the United States, and residing at Portland, in the State of Maine, 5 have invented a certain new and useful Improvement in Sanitary Shoes, of which the following is a specification.

This invention relates to shoes, and more particularly, to a shoe having a novel filler. 10 A shoe, and more particularly, a welt shoe, has a space between the insole and the outsole, which is usually filled. The filler employed heretofore has usually been a ground cork-glue mixture. Since such a filler has 15 no fiber, it will mat down. As the pressure of the foot on the insole comes in lines corresponding to the bones in the feet, the plastic filler will give, causing a permanent impression of the foot on the insole. This 20 causes the pressure to be directly transmitted to the outsole, and since this pressure is transmitted in spots, the outsole will be worn in spots along the lines of greatest pressure. Such a filler can give no lateral 25 support to the outsole, since it has no resiliency, and is, moreover, plastic, and since a bending pressure often comes laterally on an insole, the result will be that the sole will round, thus not only presenting an unattractive appearance, but also causing unusual wear.

A shoe should be comparatively flexible longitudinally but comparatively rigid laterally, in order to keep the sole flat. A composition filler does not, however, give this 35 lateral support. Moreover, such a filler has no cushioning effect at all, so that the shoe will be hard and uncomfortable to tender feet. Moreover, a composition filler gives no 40 ventilation, but holds the moisture in the shoe, and, moreover, since it is put in moist, the shoe will not be dry and sanitary. Moreover, the insole, filler and outsole become matted together, so as to form, in effect, an 45 integral mass. Under these conditions, moisture from the outer sole, as well as the perspiration from the inner sole, is conducted from one to the other. Since there is no opportunity for ventilation, and, therefore, evaporation of this moisture, the drying 50 will be slow, so that the resultant shoe is not sanitary.

Some of the objects of this invention, therefore, are to provide a shoe, the filler of 55 which has the desired characteristics of flexibility longitudinally and comparative

rigidity transversely, which acts as a cushion, permits ventilation, and is sanitary.

Further objects will appear from the detail description taken in connection with the 60 accompanying drawing, in which:

Figure 1 is a longitudinal section of a shoe embodying this invention; Fig. 2 is a bottom view with the outsole removed, the view being taken on the line 2—2, Fig. 1; 65 Fig. 3 is a section on the line 3—3, Fig. 1; Fig. 4 is an enlarged detail of Fig. 2; and, Fig. 5 is an enlarged detail section on the line 5—5, Fig. 3.

Referring to the accompanying drawing, 70 10 designates the insole, 11 the upper, 12 the welt, and 13 the outsole of a welt shoe. These parts may be of usual construction, and made in a manner well known to those skilled in the art. It will be noted that a 75 space is left between the insole and the outsole, which, as described above, is usually filled with a filler.

The filler comprises bundles 20 of fibrous stalks, such as cured grass, these bundles 80 being about three-sixteenths of an inch in diameter and stitched or woven together by threads 21. The filler may be made to conform to the space inside of the channel lip of the insole, but the bundles are arranged 85 with the stalks transversely of the shoe sole. A cover 22, of linen or similar fabric, may be cemented to one face of the stitched bundles. In the manufacture of the shoe, the filler is laid on the insole with the fabric 90 22 next to the insole, and the outsole is then attached in the usual manner.

The filler acts as a natural cushion, since it is entirely resilient, and it will, after being compressed, spring back. Since the 95 stalks are arranged cross wise of the sole, the longitudinal flexibility of the shoe sole is not impaired. Transversely, however, the bundles of the unbroken stalks form a comparatively rigid backing, so that considerable 100 resistance is offered to transverse flexure of the sole. The sole will, therefore, retain its flat shape, and will not become rounded as in other constructions. On account of the air space in the filler it is a 105 good nonconductor of heat, and is also very light.

The filler will not mat down in any place, even though under continual pressure, as is the case where felt or composition fillers 110 are used. The nonmatting qualities of the filler prevent pressure in any particular

- point from being conducted directly to the outsole, but the pressure will be transmitted over practically the entire surface of the filler to the outsole, so that the outsole will wear evenly, and, of course, will wear much longer. Moreover, this filler will not crawl or become displaced under continued wear, as is the case with other fillers, since it is practically an integral structure.
- 10 Since this filler is of open construction providing air spaces, it allows a better ventilation, and, in case the insole and outsole should become wet, they will dry out much more readily, since there is no direct contact between the soles, but there is always an air space containing a dry filler. The shoe is, therefore, entirely sanitary, and has great advantages from a medical standpoint.
- 20 It is obvious that various changes may be made in the details of construction without departing from the spirit of this invention, and it is, therefore, to be understood that this invention is not to be limited to 25 the specific construction shown and described.

Having thus described the invention what is claimed is:

1. A shoe comprising an insole, an outsole, and a resilient filler of connected ab-

sorbent fibrous stalks between said insole and said outsole, the stalks of said filler extending transversely of the shoe, thereby rendering the shoe comparatively rigid transversely and comparatively flexible longitudinally.

2. A shoe comprising an insole, an outsole, and a filler of cured grass between said insole and said outsole, the stalks of said filler extending transversely of the 40 shoe, thereby rendering the shoe comparatively rigid transversely and comparatively flexible longitudinally.

3. A shoe comprising an insole, an outsole, and a filler of connected bundles of 45 cured grass, said bundles being arranged transversely of the shoe, thereby rendering the shoe comparatively rigid transversely and comparatively flexible longitudinally.

4. A shoe comprising an insole, an outsole, and a filler of connected fibers between said insole and said outsole, said filler having its fibers so arranged as to be comparatively rigid transversely of the shoe and comparatively flexible longitudinally of the 55 shoe.

In testimony whereof I affix my signature this 4th day of May, 1915.

HORACE B. WENTWORTH.
